DESIGN FOR A COMBINATION SMOKING STAND AND SMOKER'S ACCESSORIES

William Shlesinger, Brooklyn, N. Y., assignor to Jacob Gillman, Brooklyn, N. Y., doing business as Gillman-Baker, Brooklyn, N. Y.

Application January 10, 1935, Serial No. 54,787

Term of patent 3½ years

To all whom it may concern:

Be it known that I, William Shlesinger, a citizen of the United States of America, and a resident of Brooklyn, county of Kings, and State of New York, have invented a new, original, and ornamental Design for a Combination Smoking Stand and Smoker's Accessories, of which the following is a specification, reference being had to the accompanying drawing, forming a part hereof. In the drawing:

Fig. 1 is a perspective view of the combination smoking stand and smoker's accessories, and

Fig. 2 is a plan view of the same.

I claim:

The ornamental design for a combination smoking stand and smoker's accessories as shown.

WILLIAM SHLESINGER.
